METHOD AND APPARATUS FOR CONTROLLING THE HEATING OF A FLUID

Maynard D. Church, Wellsville, N. Y., assignor to Moore Steam Turbine Corporation, Wellsville, N. Y., a corporation

Application September 11, 1931
Serial No. 562,389

25 Claims. (Cl. 257—2)

This invention relates to a method and apparatus for controlling the temperature of water or other fluid heated by the exhaust steam from a steam turbine or other type of steam engine.

5 It is common practice to use the exhaust steam from a steam engine at a pressure below atmospheric pressure for heating water or other fluids. In this case the fluid is used as a cooling medium in the condenser attached to the exhaust of the engine. It is usually true, however, that the 10 quantity of exhaust steam from the engine and the quantity of fluid to be heated are not in the proper relation to always produce a sufficient vacuum in the engine exhaust and at the same time to maintain the desired exit-temperature 15 of the fluid. This fact is of great importance where the heated fluid is to be used in process work where a uniform temperature is desired.

The principal object of the present invention 20 is to provide a method and apparatus by means of which a sufficient vacuum may be maintained in the condenser and at the same time a uniform exit-temperature of a quantity of the fluid to be heated is obtained.

25 The principal feature of the invention by which this object is attained resides in the provision of two independent streams of cooling fluid and the regulation of the condensing action of one of said streams to control the heating effect of the exhaust steam upon the other stream.

In one form of the invention this is accomplished by the use of two independent condensers, each receiving a portion of the exhaust steam from the engine. The amount of the exhaust steam passing to each condenser is regulated so that one condenser receives just sufficient steam to heat its cooling fluid to the desired temperature.

In another form of the invention also using 40 two independent condensers the rate of supply of cooling fluid to one condenser is varied to condense a greater or less amount of steam. This variation is accomplished in such a manner that the remainder of the steam passing to the second 45 condenser is just sufficient to heat the cooling fluid therein to the desired temperature.

In still another form of the invention the two streams of cooling fluid are independently passed through a single condenser and the rate of supply of one is varied to control the heating effect of the exhaust steam upon the other.

Other objects and features of the invention and the full nature thereof will be understood from the following description and claims and the attached drawings.

Fig. 1 is a diagrammatic drawing of an arrangement of the apparatus used in carrying out the invention in one of its forms. Fig. 2 is a sectional view through a portion of a temperature responsive device used for regulating the condensing action of one of the condensing units. Fig. 3 is an elevational view of one of the parts shown in Fig. 2. Figs. 4, 5, and 6 are similar views to Fig. 1 of other forms of apparatus for carrying out the invention.

In Fig. 1 a steam turbine 10 has its exhaust conduit 11 connected to an expansion joint 12 in turn connected to a T-fitting 13. One run of the fitting 13 is connected to an elbow 14 in turn connected to the exhaust steam inlet opening of 60 a condenser 15. The opposite run of the T-fitting 13 is connected to a gate-valve 16 in turn connected by a pipe 17 and elbow 18 to the exhaust steam inlet of a second condenser 19. The condenser 15 is supplied with cooling fluid 65 through an inlet pipe 20. The said fluid from the pipe 20 enters a chamber 21 and passes thence through the lower bank of tubes 22 to a chamber 23 formed by the head 24 of the condenser. From the chamber 23 the fluid passes 70 through the upper bank of tubes 25 to a chamber 26 connected to an outlet pipe 27. The condenser 19 is similarly fitted with an inlet pipe 28 and outlet pipe 29 and the circulation of fluid therein 75 is preferably the same as that in condenser 15.

The bulb 30 of a common form of thermostat is inserted in the outlet pipe 27 and is connected by a conduit 31 with a thermostat head 32. The interior of the head 32 is divided into an outer chamber 33 and an inner chamber 34 by a common form of flexible corrugated cylinder 35 which is compressed downwardly when the pressure outside of the same exceeds the pressure within and expands with the opposite pressure relationship. Within the chamber 34 a spring 95 seat 36 abuts against the closed upper end of the cylinder 35 and a compression spring 37 abuts against the under side of said seat and against the upper surface of an adjusting nut 38a threadedly engaged in a flange 38 to which 100 the head 32 is bolted. A valve stem 39 is threadedly engaged with the spring seat 36 and passes through an opening 40 in the nut 38a. By means of this apparatus, the valve stem 39 is moved upwardly and downwardly as the pressure in the chamber 33 decreases and increases in response to changes of temperature at the bulb 30.

The flange 38 forms part of a casting 41 which also has formed integrally therewith a cylinder head 42 bolted to one end of a relay cylinder 43.

The cylinder head 42 is provided with an opening 44 through which the valve stem 39 passes into the cylinder 43. Within the cylinder 43 the stem 39 is connected to a plunger 45 having portions 45a, 45b and 45c of enlarged diameter fitting within a sleeve 47 in turn fitting within the internal surface of the cylinder 43. The sleeve 47 is formed with ports 47a, 47b, 47c and 47d communicating respectively with annular recesses 48a, 48b, 48c and 48d formed in the interior wall 10 of the cylinder 43. The said sleeve is fastened to a valve stem 52 passing through a stuffing box 53 carried upon the lower cylinder head 54 of the cylinder 43. The cylinder 43 is provided with a fluid inlet pipe 55 communicating with the recess 48c. It is also provided with exhaust ports 56 and 57, the former communicating with the recess 48a and the latter communicating with the interior of said cylinder below the sleeve 47.

20 The recesses 48b and 48d are connected by pipes 60 and 61 to the lower and upper ends respectively of a valve-operating cylinder 62 mounted upon the housing of the gate valve 16. The said cylinder contains a piston 63 connected by a rod 64 to the gate 65 of the said valve. The said piston is also connected to a rod 66 in turn connected to one end of a lever 67, the opposite end of which is pivotally mounted upon a suitable stationary member 68. The stem 52 is attached to the lever 67 adjacent the pivotal mounting 68. An operating fluid under sufficient pressure to move the piston 63 is supplied through the pipe 55. The ports 56 and 57 are connected to a discharge pipe 70.

35 It will be seen that, as the temperature of the fluid in pipe 27 increases, the pressure in chamber 33 is correspondingly increased and the plunger 45 is forced downwardly. When this occurs, the enlarged portion 45c of the plunger uncovers ports 47d and the operating fluid from the pipe 55 is admitted to the upper end of the cylinder 62 through ports 47c and 47d and pipe 61. At the same time, enlarged portion 45b of the plunger 45 uncovers ports 47b and fluid may 40 escape from the lower end of cylinder 62 through pipe 60, ports 47b, 47a and 56 to the drain pipe 70. The piston 63 is, therefore, downwardly moved to move the gate 65 toward its fully 45 opened position. This movement of the piston 63 also rocks the lever 67, causing a downward movement of the valve stem 52 and the sleeve 47. When this latter movement is sufficient to bring ports 47b and 47d into register with enlarged 50 portions 45b and 45c of the plunger 45, the supply of operating fluid to cylinder 62 is stopped. Thus a given increase of temperature in the pipe 27 results in a predetermined opening movement of the valve gate 65. Similarly, a given decrease 55 of temperature in the pipe 27 results in a corresponding closing movement of the said valve gate.

60 The opening and closing movements of the gate valve 16 proportion the flow of exhaust steam between the condensers 15 and 19. If the temperature in pipe 27 momentarily exceeds a desired predetermined temperature, the valve 16 is opened to permit a larger proportion of the exhaust steam to pass to the condenser 19. The amount of steam delivered to condenser 15 is, 65 therefore, reduced and the temperature of the fluid leaving the said condenser is correspondingly reduced. Similarly, if the temperature of the water leaving the condenser is momentarily dropped below the desired degree, the valve 16

is partially closed and more steam is supplied to the condenser 15. The heated cooling fluid leaving the condenser is, therefore, maintained at a substantially uniform temperature and may be used for processes where such a uniform temperature is necessary. At the same time, there is always available sufficient condenser capacity to maintain a sufficient vacuum in the turbine exhaust. To adjust the apparatus to give any predetermined temperature of the heated fluid within limits, it is only necessary to change the pressure of spring 37 by changing the adjustment of nut 38a. The position of plunger 45 for each degree of fluid temperature is thereby changed and the average position of gate valve 16 is changed accordingly.

80 In Figure 4, there is shown a form of apparatus by means of which the same result is obtained by regulating the supply of cooling fluid to the condenser 19. In the said figure, like numbered parts have the same construction and functions as in Figure 1. The operating cylinder 62 is, however, connected to a gate valve 116 which controls the supply of cooling fluid to the inlet pipe 28 of the condenser 19. By means 85 of this arrangement, an increase or decrease of the temperature in pipe 27 is effective to partially open or close the valve 116 and to admit a larger or smaller supply of cooling fluid to the condenser 19. The said condenser, therefore, operates to 90 condense a larger or smaller portion of the exhaust steam from the turbine 10 and the amount of steam supply to the condenser 15 is correspondingly varied. The temperature of the cooling fluid leaving the condenser 15 is, therefore, 95 maintained substantially constant as with the previously described arrangement of apparatus.

95 In Figure 5, there is shown a further modification of the apparatus. In this figure, like numbered parts have the same construction and function as in Figure 1. The conduit 31 is, however, connected to a thermostat head 132 which is adapted to control a rheostat 133 in a well known manner. The said rheostat is arranged to control the speed of a motor 171 which in turn drives 115 a pump 172 which supplies cooling fluid to the inlet 28 of the condenser 19. The rheostat and thermostat head are so adjusted that the speed of the motor 171 is increased to supply 120 more cooling fluid to the condenser 19 when the temperature in pipe 27 is increased and to decrease the speed of said motor when said temperature is decreased. Thus the effective condensing action of the condenser 19 is varied as 125 before to control the temperature of the cooling fluid leaving the condenser 15.

130 In Figure 6, there is shown a still further modification of the apparatus for carrying out the invention. This form is for use when it is desired to heat the fluid to a temperature higher 135 than is possible with the exhaust steam normally leaving the turbine. In this modification, a multi-pressure-stage turbine 210 has its exhaust 140 211 connected to an expansion joint 212 in turn connected to the exhaust steam inlet of a condenser 213. The said condenser is supplied with two independent streams of cooling fluid, one entering through an inlet pipe 214, passing through the upper bank of tubes 215 and leaving by a pipe 216, the other being supplied through 145 a pipe 217, passing through a gate valve 218 and the lower bank of tubes 219 and discharging through a pipe 220. The first of said streams of fluid, upon leaving the condenser 213, passes into a heater 221 and is discharged therefrom through 150

a pipe 222. The heater 221 is supplied through pipe 223 with steam taken from one of the intermediate pressure stages of the turbine 210 and consequently at a higher pressure and temperature than the exhaust steam. The said steam is, therefore, able to heat the stream of cooling fluid to a higher degree than can be done by the exhaust steam within the condenser 213. The bulb 230 of a thermostatic device is inserted in the pipe 222 and is connected by a conduit 231 to a thermostat head 232. The said head is of the same construction as the thermostat head 32 previously described and is connected to a relay cylinder 243 and a valve-operating cylinder 262 similar in construction and operation to the cylinders 43 and 62 previously described. The operating cylinder 262 serves to operate the valve 218.

By means of this apparatus, the rate of supply of cooling fluid to the lower bank of tubes 219 is decreased and increased in accordance with the decrease and increase of temperature of the outgoing cooling fluid in pipe 222. With an increased rate of supply, the fluid in these lower tubes absorbs an increased proportion of the heat of the exhaust steam and a smaller amount of heat is left to be absorbed by the fluid in the upper bank of tubes. Similarly, with a decrease in flow of fluid in the lower bank of tubes, more heat is absorbed by the fluid in the upper tubes. Thus the total heating effect of the condenser 213 and heater 221 upon the stream of fluid passing therethrough is controlled to preserve a substantially uniform outgoing temperature.

In the foregoing description, several alternative forms of the apparatus have been described. It is evident that combinations and variations of the specific elements of the various forms may be made without departing from the scope of the invention,—for example, in the forms of apparatus shown in Figures 4 and 5, a single condenser having two streams of fluid, such as shown in Figure 6, may be used. It is also possible to use the auxiliary heater 221 as shown in Figure 6 with any of the types of apparatus shown in Figures 1, 4 and 5. It is also possible to use any two of the types of control in the same installation when extremely close regulation of the temperature of a large stream of fluid is required,—for example, the proportioning of the exhaust steam to the two condensers as shown in Figure 1 may be used in the same installation with the control of the cooling fluid supply shown in Figures 4 and 5. Similarly, the two methods of control of cooling fluid supply shown in Figures 4 and 5 may be used together in the same installation. The method of Figure 5 may be used with a steam engine or turbine driving the pump 172 instead of the motor 171. The governor of the steam engine or turbine is then controlled by the thermostat head 132 to produce the desired speed variation. It is also possible to use the method of Figure 6 with a compound steam engine instead of a multi-pressure-stage steam turbine. In the appended claims, the term "steam engine" is intended to include turbines and other types of steam-operated prime movers. The term "a pair of condensing systems", used in the claims, is intended to include a construction such as the condenser 213 wherein the two condensing systems are included in a single unit.

The invention claimed is:

1. A method of controlling the heating of a fluid by the exhaust steam from a steam engine, comprising condensing the steam by two inde-

pendent streams of fluid, and controlling the effective action of one of said streams to regulate the outgoing temperature of the other.

2. A method of controlling the heating of a fluid by the exhaust steam from a steam engine, comprising condensing the steam by two independent streams of fluid, and controlling the effective action of one of said streams to maintain the outgoing temperature of the other of said streams substantially constant. 80

3. A method of controlling the heating of a fluid by the exhaust steam from a steam engine, comprising condensing the steam by two independent streams of fluid, and controlling the effective action of one of said streams to prevent the outgoing temperature of the other of said streams from exceeding a predetermined degree. 85

4. A method of controlling the heating of a fluid by the exhaust steam from a steam engine, comprising condensing the steam by two independent streams of fluid, and automatically controlling the effective action of one of said streams in response to variations in the outgoing temperature of the other of said streams to regulate said outgoing temperature. 90

5. A method of controlling the heating of a fluid by the exhaust steam from a steam engine, comprising condensing the steam by two independent streams of fluid, and automatically controlling the effective action of one of said streams in response to variations in the outgoing temperature of the other of said streams to maintain said outgoing temperature substantially constant. 105

6. A method of controlling the heating of a fluid by the exhaust steam from a steam engine, comprising condensing the steam by two independent streams of fluid, and automatically controlling the effective action of one of said streams in response to variations in the outgoing temperature of the other of said streams to prevent said outgoing temperature from exceeding a predetermined degree. 110

7. A method of controlling the heating of a fluid by the exhaust steam from a steam engine, comprising condensing the steam by two independent streams of fluid, and controlling the rate of supply of one of said streams to regulate the outgoing temperature of the other. 120

8. A method of controlling the heating of a fluid by the exhaust steam from a steam engine, comprising condensing the steam by two independent streams of fluid, and controlling the rate of supply of one of said streams to maintain the outgoing temperature of the other substantially constant. 125

9. A method of controlling the heating of a fluid by the exhaust steam from a steam engine, comprising condensing the steam by two independent streams of fluid, and automatically controlling the rate of supply of one of said streams in response to variations in the outgoing temperature of the other to regulate said outgoing temperature. 130

10. A method of controlling the heating of a fluid by the exhaust steam from a steam engine, comprising condensing the steam by two independent streams of fluid, and automatically controlling the rate of supply of one of said streams in response to variations in the outgoing temperature of the other to maintain said outgoing temperature substantially constant. 140

11. A method of controlling the heating of a fluid by the exhaust steam from a steam engine, comprising dividing said exhaust steam between two condensing systems, condensing the steam 150

- in each system by an independent stream of condensing fluid associated therewith, and proportioning the amount of exhaust steam to the two systems to regulate the outgoing temperature of one of said streams of fluid. 5 19. Apparatus for controlling the heating of a fluid by means of exhaust steam from a steam engine including a pair of condensing systems for receiving and condensing said exhaust steam, means for supplying an independent stream of cooling fluid to each system, and means for controlling the rate of supply of the cooling fluid to one of said systems to maintain the temperature of the heated cooling fluid leaving the other of said systems substantially constant. 80 85
12. A method of controlling the heating of a fluid by the exhaust steam from a steam engine, comprising dividing said exhaust steam between two condensing systems, condensing the steam 10 in each system by an independent stream of condensing fluid associated therewith, and proportioning the amount of exhaust steam to the two systems to maintain the outgoing temperature of one of said streams substantially constant. 15 18. A method of controlling the heating of a fluid by the exhaust steam from a steam engine, comprising dividing said exhaust steam between two condensing systems, condensing the steam in each system by an independent stream of condensing fluid associated therewith, and automatically proportioning the amount of exhaust steam to the two systems in response to the outgoing temperature of one of said streams of fluid to regulate said outgoing temperature. 20 25. 14. A method of controlling the heating of a fluid by the exhaust steam from a steam engine, comprising dividing said exhaust steam between two condensing systems, condensing the steam in each system by an independent stream of condensing fluid associated therewith, and automatically proportioning the amount of exhaust steam to the two systems in response to the outgoing temperature of one of said streams of fluid to maintain said outgoing temperature substantially 30 constant. 35 15. Apparatus for controlling the heating of a fluid by means of exhaust steam from a steam engine including a pair of condensing systems for receiving and condensing said exhaust steam, means for supplying an independent stream of cooling fluid to each system, and means for varying the rate of heat transfer in one of said systems to regulate the temperature of the heated cooling fluid leaving the other of said systems. 40 45 16. Apparatus for controlling the heating of a fluid by means of exhaust steam from a steam engine including a pair of condensing systems for receiving and condensing said exhaust steam, means for supplying an independent stream of cooling fluid to each system, and mechanism automatically responsive to the temperature of the heated cooling fluid leaving one of said systems for varying the rate of heat transfer in the other of said systems to regulate said temperature. 50 55 17. Apparatus for controlling the heating of a fluid by means of exhaust steam from a steam engine including a condensing system for removing a portion of the heat from said exhaust steam to heat said fluid, a second condensing system for removing the surplus heat of said exhaust steam, and mechanism automatically responsive to the temperature of said fluid leaving the first system for varying the rate of absorption of heat in the second system to regulate said temperature. 60 65 18. Apparatus for controlling the heating of a fluid by means of exhaust steam from a steam engine including a pair of condensing systems for receiving and condensing said exhaust steam, means for supplying an independent stream of cooling fluid to each system, and means for controlling the rate of supply of the cooling fluid to one of said systems to regulate the temperature of heated cooling fluid leaving the other system. 70 75 19. Apparatus for controlling the heating of a fluid by means of exhaust steam from a steam engine including a pair of condensing systems for receiving and condensing said exhaust steam, means for supplying an independent stream of cooling fluid to each system, and means automatically responsive to the temperature of heated cooling fluid leaving one of said systems for proportioning the exhaust steam to the two systems to maintain said temperature substantially constant. 80 85 90 95 100 105 110 115 120 125 130 135 140 145 150
